UNITED STATES PATENT OFFICE.

AXEL W. CARLSON, OF MINNEAPOLIS, MINNESOTA.

THERMALLY-RELEASED CHECK-VALVE.

1,082,107.

Specification of Letters Patent.

Patented Dec. 23, 1913.

Application filed March 22, 1913. Serial No. 756,171.

To all whom it may concern:

Be it known that I, AXEL W. CARLSON, a citizen of the United States, residing at Minneapolis, in the county of Hennepin and State of Minnesota, have invented certain new and useful Improvements in Thermally-Released Check-Valves; and I do hereby declare the following to be a full, clear, and exact description of the invention, such as will enable others skilled in the art to which it appertains to make and use the same.

My invention has for its object to provide a safety device for automatically cutting off the supply of gas or gasoline from storage tanks, service pipes, and the like, in case of fire or when the temperature in a room has risen to a predetermined degree.

To the above ends, generally stated, the invention consists of the novel devices and combinations of devices hereinafter described and defined in the claim.

The invention is illustrated in the accompanying drawings, wherein like characters indicate like parts throughout the several views.

Referring to the drawings: Figure 1 is a view in side elevation, showing my invention; Fig. 2 is a plan view of the same; and Fig. 3 is a view partly in side elevation and partly in longitudinal section, taken on the line $x^3 x^3$ of Fig. 2.

The numeral 1 indicates a gas supply pipe or conduit having interposed therein a valve casing 2. Within the valve casing 2 is a transverse partition 2^a having formed therein a port 3, which affords communication through the valve casing 2. The port 3 is adapted to be closed by a check valve 4, having a valve stem 5. One end of this valve stem 5 works through a stuffing box 6 on the valve casing 2, and the other end thereof is seated, for endwise sliding movement, in an internal seat 7, formed in a screw plug 8, which normally closes an opening in the

valve casing 2, provided for inserting the valve 4 therein and removing said valve therefrom. A coiled spring 9 is mounted on the valve stem 5, is compressed between the valve 4 and screw plug 8 and tends to yieldingly hold said valve in a position to close the port 3 in the partition 2^a, thereby

cutting off communication through the valve casing 2.

The parts thus far described may be of the standard or any desired construction. 55

Suitable means, including a fusible element, is provided for normally holding the valve 4 open, against the tension of the spring 9, to permit free passage of gas through the valve casing 2. This lock comprises a yoke 10, having its transverse portion perforated and telescoped onto the hub of the stuffing box 6. A set nut 11 having screw threaded engagement with the hub of the stuffing box 6 is provided for clamping 60 the intermediate portion of the yoke 10 onto the valve casing 2. One of the prongs of the yoke 10 is bent to form a hook 12, and the other prong thereof is bent laterally outward, to afford an extension 13. 70

Extending transversely across the path of movement of the outwardly projecting end of the valve stem 5 and connected to the prongs of the yoke 10 is a lever 14. One end of the lever 14 is provided with a hook 15, 75 which has interlocking engagement with the hook 12 of the yoke 10, to afford a fulcrum for the lever 14. The other or free end of the lever 14 is secured to the yoke extension 13 by fusible solder 16. In securing the 80 lever 14 to the prongs of the yoke 10, it is necessary to force the valve stem 5 inward, thereby moving the valve 4 out of engagement with the port 3 against the tension of the spring 9. 85

The valve 4 is normally held in an open position by the lever 14 until the solder 16 fuses under the required temperature. The fusing of the solder 16 releases the lever 14 from the yoke extension 13, and the action 90 of the compressed spring 8 on the valve stem 5 swings the lever 14 outward on its fulcrum, thereby permitting the valve 4 to seat and close the port 3, thus cutting off the supply of gas. 95

The above described device, in actual usage, has been found highly efficient for the purpose had in view.

What I claim is:

The combination with a conduit, of a valve 100 casing interposed in said conduit, a stuffing box on said casing, a valve in said conduit

having a stem working through said stuffing box, a spring tending to close said valve, a yoke having its transverse portion secured to the hub of said stuffing box, one of the prongs 5 of said yoke having a hook and the other prong thereof being bent laterally, and a lever having, at one end, a hook separably fulcrumed on the hook of said yoke and having its other end secured, by fusible solder, 10 to the laterally bent portion of said prong,

the intermediate portion of said lever having engagement with said valve stem to normally hold said valve open.

In testimony whereof I affix my signature in presence of two witnesses.

AXEL W. CARLSON.
